UNITED STATES PATENT OFFICE.

NEWELL P. COWELL, OF PITTSBURG, PENNSYLVANIA, ASSIGNOR OF ONE-HALF TO WILLIAM MILLIGAN, OF ALLEGHENY, PENNSYLVANIA.

MARKER FOR PRESSED STEEL.

SPECIFICATION forming part of Letters Patent No. 724,163, dated March 31, 1903.

Application filed October 23, 1902. Serial No. 128,375. (No model.)

To all whom it may concern:

Be it known that I, NEWELL P. COWELL, a citizen of the United States of America, residing at Pittsburg, in the county of Allegheny and State of Pennsylvania, have invented certain new and useful Improvements in Markers for Pressed Steel, of which the following is a specification, reference being had therein to the accompanying drawings.

10 This invention relates to certain new and useful improvements in markers or punchers for pressed-steel work, and has for its object to provide a marker which may be either employed to automatically mark or punch the 15 work being shaped or operated by hand.

The invention contemplates the provision of a marker or puncher which is arranged within one of the walls of the die in any desired position, whereby as the article is being 20 shaped one or more marks are produced thereon or one or more holes punched therein, the marks indicating the places which are thereafter to be punched or drilled to produce the bolt or rivet openings.

25 Heretofore when the article was produced it had to subsequently be bored or, in other words, provided with openings to receive the securing means, the shaped article being first cooled and the positions for the bolt-openings 30 afterward determined. The present invention produces the marks for bolt-openings, as heretofore stated, while the article is being shaped, and it will therefore be apparent that when the article comes from the die it is in 35 condition to be punched or drilled and the openings in each instance will be found to be true. By simply making the punchers which produce the marks of a length and size conforming to the hole it is desired to produce 40 the punchers may be employed for forming the holes, thus dispensing with any subsequent punching or drilling.

In describing the invention in detail reference is had to the accompanying drawings, 45 forming a part of this specification, and wherein like numerals of reference indicate like parts throughout the several views, in which—

Figure 1 is a view in perspective of a portion of a die embodying the present invention. Fig. 2 is a vertical sectional view of

my improved marker or puncher. Fig. 3 is a front elevation of the same. Fig. 4 is a view taken on the line 4 4 of Fig. 2. Fig. 5 is a section taken on the line 5 5 of Fig. 2. 55 Fig. 6 is a perspective view of the plunger.

In the drawings the reference-numeral 1 indicates a suitable die in which is arranged an approximately rectangular casing 2, said casing being provided in one of its walls with 60 a series of apertures 2', arranged in vertical alinement. Although in the drawings I have shown but three openings, it will be obvious that I may employ in lieu thereof a greater or less number without departing from the 65 spirit of my invention. The function of these openings will be hereinafter explained.

3 indicates the casing of my improved marker or puncher, which is provided at its upper edge with an outwardly-extending 70 flange 4, provided with openings to receive suitable securing means.

By reference to Fig. 1 it will be observed that I mount my improved marker or puncher within a die adjacent to one side of the die-casing and provide the same in its one wall with an elongated slot 5, which registers with the opening of the said casing 2. The casing 3 is hollow and is provided on its rear wall with an inclined shoulder 6, which is arranged at the upper end of the centrally-arranged thickened portion 7, which portion extends to a point adjacent to the lower end of the casing. This rear wall also carries inclined shoulders 6' 6' near the lower end, 80 85 adapted to be engaged by inclined shoulders on the plunger, as will be later described.

8 indicates a laterally-moving plate arranged within the casing and having its lower edge in engagement with the seat 9, on which 90 the said plate moves. 10 indicates a series of markers or punchers which are removably secured to the said plate and which are adapted during the movement of the plate to project through the elongated slot of the casing 95 and the apertures of the rectangular casing 2 and engage the article being shaped. In the drawings the markers or punchers are shown supported in position by means of screw-threaded bolts. It will be obvious, however, if I so desire, that I may employ other means for securing the same in position, and

I vary the number of the same to correspond with the number of openings in the die-casing 2 as they are varied; also, that by making the punchers or markers of a sufficient length 5 and of the desired size they may be employed for producing the holes, thus dispensing with any after drilling or punching.

11 indicates a plunger arranged between the plate 8 and the thickened portion 7 of the 10 casing, said plunger provided adjacent its upper end on its rear face with an inclined shoulder 6^a, adapted to engage with the inclined shoulder 6. This plunger normally has its upper end projecting through an opening 12 in the top of its casing and is capable of moving in a vertical plane. The plunger is also provided on its rear face near the lower end with inclined shoulders 13, which engage the inclined surfaces of the shoulders 6^a, spaced 15 apart and formed integral with the inner face of the rear wall of the casing adjacent its lower end.

15 15 indicate a pair of downwardly-extending hooks carried by the inner face of the 20 sliding plate 8, which hooks straddle the plunger and engage with studs 16, arranged on opposite sides and formed integral with said plunger. The plunger is provided in its front face with a vertical groove 11' to receive the 25 heads of the screws which secure the markers or punchers 10 to the plate 8, and on its rear face directly above the shoulders 13 the plunger carries a lug 12', between which and the bottom of the casing is arranged a spring 17 30 for returning the plunger to its elevated position.

From the foregoing description it will be apparent that when the plunger is depressed the inclined shoulders 6^a and 13, engaging 40 the inclined shoulders 6 and 6', will impart a sliding lateral movement to the said plunger, which movement is communicated to the sliding plate and consequently the markers or punchers are forced outward through the casing 45 and into the article being shaped. When the pressure is relieved from the plunger, the spring 17 will force the said plunger into its normal position, and as the said plate 8 is connected to the plunger through the medium of the hooks 15 the plate will be withdrawn from engagement with the die.

In practice if a two-part die is employed it will be obvious that the upper section of the die bearing upon the upper end of the plunger 55 will force the same downwardly and retain the same in this depressed position until the said upper section is moved, thereby producing the desired results. If, however, the upper die-section is not employed, the upper end of the said plunger can be depressed in any desired manner—as, for instance, by being struck by a hammer.

It will be noted that various changes may be made in the details of construction without departing from the general spirit of my invention.

Having fully described my invention, what

I claim as new, and desire to secure by Letters Patent, is—

1. The combination with a die, of a member 70 arranged in the wall thereof, a slideable plunger arranged in the rear of said member, and means whereby as the said plunger is depressed, the said marker will be moved laterally, substantially as and for the purpose described.

2. The combination with a die, of a marking or punching device arranged in the said die, said marking or punching device comprising a plate movable laterally and having a series 80 of punchers on its outer face, slideable and laterally-movable means for moving said plate laterally, and means for retracting the same.

3. In combination with a die, of a casing 85 secured in the side wall of the die, said casing provided in its outer wall with an elongated slot, a plate movable in said casing, markers or punchers secured to said plate and adapted to project through said slot, and a plunger for moving the said plate laterally, 90 substantially as described.

4. In combination with a die, of a casing secured to the side wall, said casing provided in its inner wall with an elongated slot, a plate slideably mounted in said casing and provided on its outer face with a series of marking or punching devices, a plunger for moving said plate laterally and a spring secured to the lower end of said plunger and casing, 95 substantially as described.

5. The combination with a die, of a marking or punching device secured therein, said marking device comprising a casing, and a plate laterally movable within the same, said plate being provided at its outer face with a 105 series of markers, a plunger for moving said plate laterally, said plunger having its upper end extending above the said casing, and a spring in engagement with said plunger.

6. The combination with a die, of a casing 110 secured in the side wall of the die, a plate slideably mounted in the said casing, markers or punchers secured to the outer face of said plate, a vertically-movable plunger arranged in the said casing and having oppositely-arranged lugs secured thereto, and hooks secured to the said plate and in engagement with the lugs of said plunger, substantially 115 as described.

7. A marking or punching device comprising 120 a casing, provided at its rear wall with an inclined shoulder, a plunger mounted in the said casing and having its rear side provided with an inclined shoulder in engagement with the said inclined shoulder of the 125 casing, and a plate slideable laterally within the casing, said plate provided on its outer face with a series of markers or punchers and being in engagement with said plunger, substantially as described.

8. In a device of the type set forth, a casing having a movable plate arranged therein with markers on the plate projecting without the casing, and a spring-pressed plunger in

the casing arranged to the rear of the plate, and adapted to move the latter laterally when depressed.

9. The combination with a die and a casing therein said casing provided with an aperture in one of its walls, and provided in its inner wall with an elongated slot, a plate slidably mounted in the last-named casing, a marker or puncher secured to the said plate and adapted to extend through the said elongated slot and aperture of the first-named casing, means for moving said plate laterally, and a spring secured to the lower end of said plunger and the casing.

10. The combination with a die, of a casing secured therein, said casing provided in its inner wall with a slot, and formed on the inner face of its rear wall with inclined shoulders, a plunger mounted in said casing and in engagement with said inclined surfaces of the casing, a spring in engagement with said plunger, a plate slidably mounted within said casing, a marker or puncher secured to said plate, lugs formed integral with the opposite sides of the said plunger, and hooks carried by the said plate and in engagement with said lugs, substantially as described.

11. The combination with the die, of a plate slidably mounted in the wall thereof, a marker secured to the said plate, a plunger for operating the said plate and having its upper end projecting through the top of the said die, means for automatically returning the said plunger to its normal position, and means for withdrawing the said plate as the said plunger is returned to its normal position.

12. A punching or marking attachment for dies, molds and the like, comprising a casing formed with a slot, a marker slidably mounted in the said casing and being adapted to project through the slot thereof, a plunger slidably mounted in the said casing in the rear of the said marker for actuating the same, studs secured to the said plunger, and means carried by the said marker for engagement

with the said stud, substantially as and for the purpose specified.

13. The combination with a casing formed with an elongated slot, of a plurality of markers slidably mounted in the said casing adapted to project through the said slot, and a plunger for simultaneously operating the said markers.

14. The combination with the casing, of a member slidably mounted in the said casing, markers secured to the said member, an operating means for the said member, said means being slidably mounted in the said casing and lying parallel to the said member, and means whereby as the said plunger is operated the said member will be operated.

15. The combination with the slidably-mounted plate, and the markers secured thereto, of an operating means for the said plate, said means being capable of moving both longitudinally and laterally, and means for returning the said first-named means and plate to their normal position.

16. The combination with the casing, of the slidably-mounted plate arranged in the said casing, a marker secured to the said plate, a depressible plunger lying parallel to the said plate, and means for moving the said plunger laterally of the casing as it is depressed.

17. The combination with the casing, the plate slidably mounted therein, and the markers carried by the plate, of a depressible parallel operating means for the said plate, means for moving the said first-named means into engagement with the said plate as it is depressed, and means for automatically returning the said plate and means to their normal positions.

In testimony whereof I affix my signature in the presence of two witnesses.
